UNITED STATES PATENT OFFICE.

THOMAS E. HAMPTON, OF WABASH, INDIANA.

SCHOOL DESK AND SEAT.

SPECIFICATION forming part of Letters Patent No. 364,247, dated June 7, 1887.

Application filed March 10, 1886. Serial No. 194,697. (No model.)

To all whom it may concern:

Be it known that I, THOMAS E. HAMPTON, a citizen of the United States, residing at the city of Wabash, in the county of Wabash and State 5 of Indiana, have invented certain new and useful Improvements in Combined School Desks and Seats; and I do hereby declare the following to be a full, clear, and exact description of the invention, such as will enable others skilled 10 in the art to which it appertains to make and use the same.

This invention relates to certain improvements in combined school desks and seats; and it has for its objects to provide means 15 whereby a simple, easily constructed, and cheap desk and seat may be made. These objects I attain by the means illustrated in the accompanying drawings, in which—

Figure 1 represents a perspective view of 20 my improved desk and seat; Fig. 2, a detailed view of a portion looking from the inside; Fig. 3, a vertical section thereof; Fig. 4, a detail front elevation of a portion of the main standard; Fig. 5, a modification of a portion 25 of the seat and side frames, and Fig. 6 represents a section of the frame provided with a flange on each inner face of the angle-iron composing said frame.

In the drawings, the letter A indicates my 30 combined desk and seat constructed of two side frames, B, both of which are provided at suitable points with disks C, having on their inner faces annular grooves D.

The letter E indicates the frames of the seat, 35 each having a disk, F, which are provided with annular rings G, which fit into the grooves D, above referred to, forming a hinge for the seat. To further strengthen the hinge, the disk F is provided with a central opening, H, 40 into which fits a circular projection formed on the face of a lug, I, bolted to the side frames of the desk.

On the inside of the side frames, and at suitable points, are located the seat-stops J, and 45 for additional stoppage stops are formed on the inside faces of the disks F, (indicated by the letter R.) This stop is also indicated in dotted lines in the position which it occupies when the seat is thrown up against the back. 50 In operation it co-operates with stop J. The lug I, against which it bears, is bolted to the

frame and lies in a concavity in the same in such manner that its downward extension bears laterally against the concave surface of the frame, and it is thus held against force applied through said stop R.

Stops have heretofore been made in the interior of the disk, and lugs have also been used; but I am not aware that my particular construction and combination of these parts 60 was known prior to my invention.

The stops J and R will support the seat and any weight thereon when the said seat is in a horizontal position, while should the seat be folded back, as shown in dotted lines, Fig. 2, 65 the lug I acts as a stop and prevents the said seat contacting with and injuring the back.

To put the desk and seat together, the seat-frames, with the annular rings, are fitted into the annular grooves of the desk-frames, the 70 lug with its circular projection is inserted in position, and the lug is bolted, as represented in the drawings, holding the three parts together, but still allowing the seat-frame sufficient movement to open and close. The sides having been secured together, slats L, forming the seat and back, are placed between.

To secure the slats into the frames, the frames are made at their edges in the shape of a right angle, as indicated by the letter M, and as 80 shown in Fig. 3, the horizontal face of the angle has a flange, N, which extends into a groove cut into the slats above mentioned, the slats of the seat distending the sides and holding them in that position against the desk-frames, which are held together by the slats 85 in the back and the brace P, and to secure the slats into the frames screws are used through the sides, as shown.

By the construction indicated in Fig. 6 the 90 screws may be dispensed with. Shallow grooves are formed both in the bottom and ends of the slots, adapted to closely fit corresponding flanges on the frame. Each slot is placed in suitable relation to the frame, and then forced laterally, so as to cause the flanges to enter the 95 grooves, whereby they are held in the desired position.

Having thus fully described my invention, what I claim, and desire to secure by Letters 100 Patent, is—

1. A combined desk and seat having side

frames provided with annular grooves, seat frames having disks with annular rings, the said disks also provided with central openings, lugs *l*, secured to the side frames in a cavity thereof, provided with circular projections, and stops *R*, all substantially as set forth.

2. A combined desk and seat having the seat frames pivotally seated in the side frames, and to the said frames having supports for the ma-

terial forming the seat and back, said supports having flanges extending into the ends and under sides of the said material, substantially as described.

In testimony whereof I affix my signature in presence of two witnesses.

THOMAS E. HAMPTON.
